UNITED STATES PATENT OFFICE.

JOHN W. HARVEY, OF SUNSET, TEXAS

TELEPHONE-LOCKING DEVICE.

1,090,053.

Specification of Letters Patent. Patented Mar. 10, 1914.

Application filed April 18, 1913. Serial No. 762,037.

To all whom it may concern:

Be it known that I, JOHN W. HARVEY, a citizen of the United States, residing at Sunset, in the county of Montague and State of Texas, have invented new and useful Improvements in Telephone-Locking Devices, of which the following is a specification.

This invention relates to improvements in telephone locking devices and has particular application to a device of this nature whereby the receiver hook of a telephone may be locked in inactive position and held in such position so as to prevent unauthorized persons using the telephone.

In carrying out the present invention, it is my purpose to provide a telephone lock whereby the receiver hook and consequently the switch controlling the talking circuit will be held down or in an inactive position so as to prevent unauthorized parties manipulating the phone and which may be readily unlocked and thrown out of use by those authorized to use the instrument.

It is also my purpose to provide a telephone lock which will embrace the desired features of simplicity, efficiency, durability and convenience coupled with cheapness of cost in manufacture and marketing and which may be readily applied to any type of telephone and furthermore, the locking device embodied in the present invention may be readily and conveniently unlocked and thrown out of service when persons entitled to the use of the phone wish to carry on a conversation over the latter.

With the above and other objects in view, the invention consists in the construction, combination and arrangement of parts hereinafter set forth in and falling within the scope of the claim.

In the accompanying drawing: Figure 1 is a view in elevation of a telephone equipped with my present invention, parts being broken away, and Fig. 2 is a detail perspective view of the locking device removed from the phone.

In the present instance, I have shown my invention as applied to a desk telephone, but I wish it to be understood that my invention is equally applicable to wall phones and the like and is therefore not limited to the particular application herein shown and described.

Referring now to the accompanying drawing in detail, A designates the base of a desk telephone, while a indicates the stand-

ard or post uprising from the base and carrying at the upper end thereof the usual transmitter 't. The receiver hook is indicated at r and as usual, in this style of telephone instrument, extends outwardly from the standard a and is fulcrumed therein and controls the switch of the talking circuit, the receiver proper being mounted upon the hook and designated at R.

My improved telephone locking device is indicated as an entirety by the letter L, and in the present instance comprises a strap 1 formed of a single strip of metal bent upon itself approximately centrally of its length and having the bent portion thereof formed to provide a loop 2 adapted to embrace the arm of the receiver fork or hook, the parallel members of the strap being placed in face to face contact and are formed with alining openings 3 adjacent to the free ends thereof, such openings being spaced apart along the length of the strap. A cuff or collar 4 embraces the limbs of the strap and is adapted for sliding movement thereon and, when moved toward the free ends of the limbs of the strap carries such ends toward each other so as to produce a clamping action. In the present instance, the base A of the telephone is formed with a vertically disposed aperture or passage 5 through which is passed a chain 6 or other flexible element having the lower end thereof equipped with a cross piece 7 adapted to engage the under surface of the base A so as to prevent the withdrawal of the chain from the passage in one direction. Connected to the free end of the chain is one extremity of a link 8 having the opposite end thereof formed with an aperture and designed to be inserted between the confronting faces of the limbs of the strap 1, the aperture in the free end of said link registering with the openings in the strap so as to receive a lock fastening device 9.

In use, the looped end of the strap 1 encircles the shank of the receiver hook or fork and the strap depends therefrom, while the chain 6 is passed through the passage 5 in the base, the cross piece 7 preventing the chain from moving upwardly. When it is desired to lock the hook down so as to prevent use of the phone by unauthorized persons, the collar or cuff 4 is moved upwardly along the strap so that the free ends of the limbs of the strap may be spread apart. The respective end of the link 8 is now in-

serted between the limbs of the strap and drawn upwardly therein until the chain is taut, the lock or fastening device 9 being passed through the alining openings in the 5 limbs of the strap and the respective end of the link 8 thereby locking the receiver hook down, the collar or cuff 4 being subsequently moved downwardly so as to bring the free ends of the limbs of the strap into contact 10 with the respective end of the link 8. To release the telephone receiver hook, it is only necessary to withdraw the lock or fastening device from the openings in the link and strap whereby such link and strap will separate 15 and thereby permit the receiver hook to move upwardly when the receiver is removed therefrom.

From the foregoing description taken in connection with the accompanying drawing, 20 the construction and manner of employing my invention will be readily apparent.

It will be seen that I have provided a locking device whereby a telephone may be locked against use by unauthorized persons, 25 such device comprising two members one of which is connected to the receiver hook, while the other is secured to the stationary part of the phone, and means for connecting the members to each other and holding the same 30 against separation.

While I have herein shown and described one preferred form of my invention by way of illustration, I wish it to be understood that I do not limit or confine myself to the 35 precise details of construction herein described and delineated, as modification and variation may be made within the scope of

the claim and without departing from the spirit of the invention.

I claim:

A telephone locking device formed of a strap formed of a single strip of metal bent upon itself approximately centrally of its length and having the bent portion thereof to provide a loop adapted to embrace the 45 arm of the receiver fork, the parallel members of said strap being placed in face to face contact and formed with alining openings adjacent to the free ends thereof and spaced apart longitudinally of the strap, a 50 collar embracing the limbs of said strap and adapted for sliding movement thereon to draw the free ends of the strap toward each other, a flexible element passed through an aperture in the base of the telephone and carrying at its lower end a cross piece designed to prevent the withdrawal of such flexible element, a link carried by said flexible element and having the free end thereof apertured and adapted to be disposed between the free extremities of the limbs of said strap, the aperture in the end of said link being capable of interchangeable registration with the apertures in said strap whereby the flexible element may be drawn taut, and a lock adapted to be passed through the alining apertures in the limbs of said strap and link.

In testimony whereof I affix my signature in presence of two witnesses.

JOHN W. HARVEY.
